UNITED STATES PATENT OFFICE

2,110,027

PUMP

Vincent Santarelli and John Giacobbe,
Detroit, Mich.

Application August 19, 1936, Serial No. 96,824

2 Claims. (Cl. 103—218)

Our invention relates to a new and useful improvement in a pumping mechanism and particularly that type of pumping mechanism adapted for use in pumping liquids from reservoirs, containers, and the like and the invention particularly lends itself for use on pump-operated spray mechanisms.

It is an object of the present invention to provide in a spray mechanism a pumping arrangement, so constructed and arranged, that the liquid passes into a well or sunken chamber and from there is forced by the pumping mechanism to an outlet conduit. Devices of the general type referred to have been used and are well-known and particularly the type in which a reciprocating plunger rides in the well. With the types of construction which are well-known, the reciprocating plunger, on its backward movement, is withdrawn entirely from the well in order to permit the flow of liquid into the well so that, upon re-entry of the plunger into the well, the liquid entrapped therein will be forced outwardly from the proper conduits.

An objectionable feature is that the pumping plunger may not be properly aligned with the well, so that its re-entry into the well will be retarded and the pump plunger subjected to considerable excessive air. This is due to the fact that the well is of such an inside diameter throughout its length as to snugly fit the plunger and since the plunger snugly fits the well throughout its length, it is necessary that the plunger be withdrawn from the well to permit the flow of liquid into the well. To overcome this disadvantage is one of the objects of the present invention and it is overcome by forming the well of a greater length than the stroke of the plunger and enlarging the upper end of the well so that when the plunger enters the enlarged portion of the well, considerable clearance will be present around the plunger to permit flow of liquid into the well. Since the plunger is not withdrawn from the well and since the enlarged portion is tapered gradually to the smaller portion, which snugly fits the plunger, even though the pumping mechanism might not be properly aligned with the well, the plunger will enter into snug engagement with the smaller portion of the well easily and without being subjected to excessive wear.

Another object of the invention is the provision of a simple and inexpensive valve mechanism which may be easily and quickly removed and replaced, which will function in a very efficient manner and which, when removed, will permit access to the interior of the pumping mechanism.

Another object of the present invention is the provision in a device of this kind of an agitator which will serve to agitate the liquid during the pumping operation so that when solutions are used, a settling of the dissolved material to the bottom of the tank will be prevented.

Other objects will appear hereinafter.

The invention consists in the combination of parts hereinafter described and claimed.

The invention will be understood by a reference to the accompanying drawing which forms a part of this specification and in which:

Fig. 1 is a top plan view of a spray embodying the invention.

Fig. 2 is a rear elevational view with parts broken away and parts shown in section.

Fig. 3 is a central sectional view through the pumping mechanism, enlarged, and with parts broken away.

In the drawing, I have illustrated the invention used with a tank 7 in the top 8 of which there is formed an opening in which is positioned the sleeve 9, carrying the screen 10. A cover 11 serves as a closure for the opening so that material deposited in the tank may be screened through the screen 10 and thus the passage of large particles of solid matter into the tank would be prevented. An elevated bottom 11 is formed on the tank and secured to and projecting downwardly from the bottom on one side thereof, is a well, the lower portion 12 of which is of smaller inside diameter than the upper portion 13, these portions communicating by the inclined wall 14. Mounted in the top 8; in alignment with the well, is a guide sleeve 15, through which is slidably projected the pump barrel 16, on which is fixedly mounted a head 17. This head 17 is provided with a boss 18, through which is projected the angularly turned portion 19 of the pump rod 20. Cotter pins 21 serve to retain the portion 19, projected through the boss 18. The lower end of the rod 20 is attached to the lever 22, intermediate its ends. This lever is pivoted on the pin 23, projected through the bracket 24, which is mounted on the tank 7. The pin 23 projects through one end of the lever 22 and the opposite end 25 is angularly turned to provide a gripping portion whereby the operator may grip the lever 22 and rock it on its pivot pin 23 to effect a reciprocation of the barrel 16. The barrel 16 is provided with a reduced tapered portion 26, which enters the well and carries the threaded end 27, in which is threaded one end of the plunger 28. This plunger has the portion 29, which is adapted to snugly engage the inner surface of the smaller

portion 12 of the well. An opening 30 is formed in the lower end of the plunger and closed by the ball 31, acting as a valve, this ball fitting in the pocket 32, formed in the plunger. Its removal 5 from the pocket 32 is prevented by wires 33, which are welded or otherwise suitably secured so as to extend across the pocket 32 at the upper end thereof. Thus, liquid entering through the opening 30, will raise the ball 31 from its seat and 10 may be permitted to pass into the interior of the barrel 16. Extended longitudinally of the barrel 16, is an outlet pipe 34, which terminates adjacent the lower end of the tubular portion 26 and which is secured at its upper end to the head 17 in communication with an outlet passage 35 which also 15 passes through the nipple 36, to which one end of the flexible hose or conduit 37 may be attached. This hose is connected through the valve 38 to the rigid pipe 39, which serves as a gripping portion 20 for the operator and which carries the spray nozzle 40.

In operation, a rocking of the lever 22 will effect a reciprocation of the barrel 16, which will serve to raise the plunger into the enlarged portion 25 13 of the well, so that liquid in the tank will flow into the well and fill it. It will be noted that the plunger does not withdraw from the well but merely enters the enlarged portion so that on the return or power stroke it is guided, positively, into 30 the small portion 12 and as it moves downwardly in the small portion, the liquid trapped therein, will be forced into the barrel 16, from which it will pass into the pipe 34 and through the passage 35 into conduit or hose 37. Thus a failure of the 35 plunger to enter the well is prevented and excessive wear of the plunger is prevented. Moreover, since this type of construction affords a positive guiding of the plunger into the well, the plunger may be formed from metal. It will also be noted 40 that when the plunger is unscrewed from the threaded portion 27, access to the threaded barrel 16 is afforded, thus facilitating a cleaning of the interior of the barrel 16 and affording access to the tube 34, so that it may be also cleaned, while 45 the head 17 may be permanently mounted on the barrel 16.

In order that the liquid may be constantly agitated and the deposit of sediment prevented, we mount an agitating arm 41 on the barrel 16 50 by means of the clamp 42. Consequently, since the arm 41 moves with the barrel 16, it serves to constantly agitate the liquid being pumped from the tank.

While we have illustrated and described the 55 preferred form of construction, we do not wish to limit ourselves to the precise details of struc-

ture shown, but desire to avail ourselves of such variations and modifications as may come within the scope of the appended claims.

Having thus described our invention, what we claim as new and desire to secure by Letters 5 Patent is:

1. A pumping mechanism of the class described, comprising: a liquid-receiving receptacle; a well projecting outwardly below the bottom of said receptacle, said well comprising an upper and a lower portion, said upper portion being of greater diameter than said lower portion and arranged concentric of said lower portion, and said lower portion being connected thereto by an inclined wall; a top on said receptacle; a guide sleeve 15 mounted in said top in alignment with said well; a pumping barrel slideably projected through said guide sleeve; a tapered portion on the lower end of said barrel extending into said well, said tapered portion being threaded; and a plunger 20 threaded on said threaded portion and extending into said well; means for reciprocating said barrel, said plunger upon reciprocation of said barrel in one direction moving from the larger portion of said well into the smaller portion and upon 25 reciprocation in the opposite direction moving from the smaller portion of said well into the larger portion, said plunger being non-retractable from said larger portion of said well.

2. A pumping mechanism of the class de- 30 scribed, comprising: a liquid-receiving receptacle; a well projecting outwardly below the bottom of said receptacle, said well comprising an upper and a lower portion, said upper portion being of greater diameter than said lower portion and ar- 35 ranged concentric of said lower portion, and said lower portion being connected thereto by an inclined wall; a top on said receptacle; a guide sleeve mounted in said top in alignment with said well; a pumping barrel slidably projected through 40 said guide sleeve; a tapered portion on the lower end of said barrel extending into said well, said tapered portion being threaded; a plunger threaded on said threaded portion said plunger being of size for snugly engaging in the lower 45 portion of said well, said plunger having a pocket formed therein and provided with an opening leading into said pocket, said pocket being in communication with the interior of said barrel, a ball in said pocket for closing said opening; and 50 diametrically extending means on said plunger extending across said pocket for preventing movement of said ball from said pocket into said barrel.

VINCENT SANTARELLI. 55
